UNITED STATES PATENT OFFICE.

WILLIAM J. SHELTON, OF VAN VLECK, TEXAS.

FUMIGATOR.

971,570.

Specification of Letters Patent. Patented Oct. 4, 1910.

Application filed June 22, 1909. Serial No. 503,684.

To all whom it may concern:

Be it known that I, WILLIAM J. SHELTON, citizen of the United States, residing at Van Vleck, in the county of Matagorda and State of Texas, have invented a new and useful Fumigator, of which the following is a specification.

This invention relates to an improved article especially adapted for use in fumigating poultry nests and exterminating the mites and lice which infest the same. The article can also be employed for fumigating clothes, or it may be employed for perfuming purposes, as desired.

The principal object of the invention is to provide an article which is preferably made from glass, although other material, such as porcelain or the like, can be employed equally as well, and is preferably formed in the shape of a hollow egg.

Another object of the invention is to provide a device of the class described which will permit of the same being readily and partially filled with a fumigating liquid or the like; will allow the fumes arising from the said liquid to pass out from the article, but will retain the said liquid within, irrespective of the position of the said article, and thereby prevent the said liquid from coming in contact with whatever is being fumigated.

With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing, Figure 1 is a sectional view showing the position of the liquid in one position of the article. Fig. 2 is a sectional view showing the position of the liquid in another position of the article. Fig. 3 is a sectional view showing the position of the liquid in a different position of the article, and Fig. 4 is a sectional view showing the position of the liquid in a still different position of the article.

Like reference numerals designate corresponding parts in all the figures of the drawing.

Referring to the drawing, 5 designates a hollow, preferably egg-shaped tube or shell constituting a receptacle for a fumigating liquid or powder, and is preferably formed of glass. While the receptacle is shown as being egg-shaped, and is especially advantageous in this shape, inasmuch as it can be employed as a nest egg, I do not wish to limit myself thereto, as other forms, such as spherical or rectangular shapes, can be employed equally as well. Extending inwardly from, and preferably integral with the shell, is an open-ended tube 6 having its inner end 7 terminating near the center of the said receptacle, said tube also forming an opening 8 in the shell, constituting the sole exit and inlet.

In practice, coal-oil or other suitable fumigating liquid or a powder is poured into the receptacle through the inwardly extending tube 6 until the level of the said liquid closes the open inner end 7 of said tube as clearly shown by reference to Fig. 1 of the drawing. The fumes arising from the said liquid will readily pass out through the tube 6; but the liquid, however, will be forced to remain within the receptacle because of the fact that the open inner end 7 of the tube will always be above the level of the liquid, irrespective of the position assumed by the article, as clearly shown in all the figures of the drawing.

The device can be packed in trunks along with clothing and filled with material obnoxious to moths, and under these circumstances may be constructed of any suitable shape, as the egg-shape is not particularly desirable for such purposes. Whether used for this purpose or for a nest egg it is admirably adapted to perform the functions herein stated.

What I claim is:—

1. A hollow nest egg formed of glass and constituting a receptacle for containing a fumigating element, said receptacle being provided with an inwardly extending and open-ended integral tube, the inner end being arranged near the center of the receptacle, the said tube adapted to permit of the egress of the fumes of the said element, but not the element, irrespective of the position of the receptacle.

2. A hollow nest egg comprising a non-porous shell constituting a receptacle for containing a fumigating element, said receptacle being provided with an open-ended

integral tube which extends inwardly from the butt end of the egg, the inner end of the tube being arranged near the center of the receptacle and above the level of the element, 5 the said tube being adapted to permit of the egress of the fumes of the said element, but not the element, irrespective of the position of the receptacle.

In testimony, that I claim the foregoing as my own, I have hereto affixed my signature in the presence of two witnesses. 10

WILLIAM J. SHELTON.
